(57) **CLAIM**

The ornamental design for a display screen or portion thereof with animated graphical user interface, as shown and described.

DESCRIPTION

FIG. 1 is a first image in a sequence for a display screen or portion thereof with animated graphical user interface showing our new design;

FIG. 2 is a second image thereof;

FIG. 3 is a third image thereof;

FIG. 4 is a fourth image thereof;

FIG. 5 is a fifth image thereof;

FIG. 6 is a sixth image thereof; and,

FIG. 7 is a seventh image thereof.

The appearance of the animated image on the display screen sequentially transitions between the images shown in FIGS. 1–7. The process in which, and the period during which, one image transitions to another image forms no part of the claimed design. The outermost broken line illustrates a display screen and the remainder of the broken lines illustrate portions of the animated graphical user interface. None of the broken lines form part of the claimed design.
